ISAAC PARDEE, OF VINELAND, NEW JERSEY, AND R. C. PARVIN, OF FOREST GROVE, NEW JERSEY, ASSIGNORS TO R. C. PARVIN.

Letters Patent No. 65,263, dated May 28, 1867.

IMPROVEMENT IN STUMP-EXTRACTORS.

The Schedule referred to in these Letters Patent and making part of the same.

TO ALL WHOM IT MAY CONCERN:

Be it known that we, ISAAC PARDEE, of Vineland, in the county of Cumberland, and in the State of New Jersey, and R. C. PARVIN, of Forest Grove, in the county of Gloucester, and said State of New Jersey, have invented a new and improved Stump-Extractor; and we do hereby declare that the following is a full, clear, and exact description thereof, which will enable others skilled in the art to make and use the same, reference being had to the accompanying drawings, forming a part of this specification.

This invention relates to a new and improved machine for extracting stumps, elevating stone, and lifting or raising other heavy bodies.

The invention consists of two rack-bars, fitted in a socket provided with pawls, and placed loosely upon a suitable framing, the rack-bars having a lever attached to their lower ends, and all arranged as hereinafter fully shown and described, whereby a very simple, economical, and efficient device for the purpose specified is obtained—one not liable to get out of repair or have its working parts deranged by use. In the accompanying sheet of drawings—

Figure 1 is a side view of our invention.

Figure 2, a vertical section of the same, taken in the line *x x*, fig. 1.

Similar letters of reference indicate like parts.

A represents a framing composed of a horizontal bed-piece, B, supported by inclined bars C, two at each side, the lower ends of said bars being attached to bases or sills D, or to a truck when the raised articles are to be transported from the places where they were raised. E represents a socket, which may be of cast iron. This socket has a rounded or semi-cylindrical bottom, which is fitted and works in a corresponding-shaped recess made in the upper surface of the bed-piece B, as shown clearly in fig. 2. F F represent two rack-bars, which pass up loosely through the socket E, and have pawls G G engaging with them. These pawls rest on a ledge, a, within the socket, and have their lower ends rounded, as shown at b, in fig. 2, which rounded edges give the upper ends of the pawls a tendency to keep engaged with the teeth of the rack-bars. This will be fully understood by referring to fig. 2, in which it will be seen that the lower ends of the pawls are rounded at their inner sides, and consequently deprived of a support which would have a tendency to keep them upright. By this arrangement springs which are usually employed in connection with pawls are avoided. In order to disengage the pawls from the rack-bars, each pawl has a cord or small wire, c, attached, and these cords or wires pass through holes in the side of the socket so that they may be readily grasped when necessary. The lower ends of the rack-bars F F are connected by pivots d d to a metal lever, H, the ends of which have loops e attached to receive wooden handles I I. The handles, it will be seen, are simply an extension of the lever, and to the centre of the latter, at a point a trifle below, but in a line midway between the pivots d d, which attach the rack-bars to the lever, there is secured a pendent bail, J, in which a ring, K, is placed. This ring K has two bars, L M, fitted or placed upon it, the bar L having an eye or hole, f, made in it near its lower end, and the other bar, M, having a rod, N, secured to it by a pivot, (g, see fig. 1.)

The operation is as follows: If a stump is to be extracted the chain is adjusted around it, and the rod N of the bar M passed through a link, b, thereof, and then through the eye f of the bar L, (see fig. 1.) The lever H is then operated, worked up and down by a man at each handle I, and the rack-bars F F raised alternately the distance of one tooth, the pivots d d serving as fulcra alternately, and the pawls G serving to hold the rack-bars.

It will be seen that by this simple arrangement a powerful leverage is obtained, and in consequence of the socket E being loose on the bed-piece B, and rounded at its bottom, the former is allowed to turn and adjust itself to conform to the line or position the chain will assume under the pull of the rack-bars. The bars C may have handles O attached for the convenience of carrying the machine or adjusting it in position, and the machine, in cases where it is desired to carry or transport the elevated article from the place where it was elevated or raised, may be placed on a truck.

Having thus described our invention, what we claim as new, and desire to secure by Letters Patent, is—

The pawls G G, resting upon the ledge a of the socket E, with their lower inner corners rounded, as shown at b, so that their upper ends will fall by their own gravity against the ratchet-bars F, and engage therewith, when constructed and arranged as herein shown and described.

ISAAC PARDEE,
R. C. PARVIN.
